United States Patent Office.

CHRISTOPHER MEYER, OF NEW YORK, N. Y.

Design No. 4,769, dated April 4, 1871.

DESIGN FOR THE ORNAMENTATION OF RUBBER-SHOES.

The Schedule referred to in these Letters Patent and making part of the same.

To all whom it may concern:

Be it known that I, CHRISTOPHER MEYER, of the city of New York, in the county and State of New York, have invented a new and original Design for India-Rubber Shoes; and I do hereby declare that the following is a full, clear, and exact description thereof, which will enable others skilled in the art to make and use the same, reference being had to the accompanying drawing forming part of this specification.

This design consists in the ornamentation of rubber shoes.

Their front upper portion is roughened, or made to appear more or less like woven fabric, leaving transverse stripes or spaces, which have the appearance of the ordinary glazed rubber.

A scalloped edge is formed around the ornamental ground.

I claim as my invention—

The design for the ornamentation of India-rubber shoes, as shown.
